SECTIONAL WOOD BUILDING

Neal T. MacKenzie, St. Paul, Minn., assignor to
General Timber Service, Inc., St. Paul, Minn., a
corporation of Delaware

Application March 20, 1942, Serial No. 435,539

9 Claims. (Cl. 20—1.2)

This invention relates to a sectional wood building particularly although not exclusively adapted for use as a grain storage bin.

It is an object of the invention to provide a wooden building having a multiplicity of novel wall units adapted to form a substantially cylindrical structure which will withstand outward pressure from within such as that produced when the building is filled with grain.

Another object is to provide in a building of this class novel, prefabricated wall sections adapted to be erected and fastened together quickly and easily.

A further object is to provide for such buildings an improved joint which will remain closed under severe outward pressure and other stresses to which it is subjected, including those due to the swelling and shrinking of the wood.

Referring to the accompanying drawings:

Figure 1 illustrates one of my improved buildings in elevation;

Fig. 2 is a partial plan view of the same with portions of the floor and roof removed;

Fig. 3 is a front elevation of a panel or wall section having a door opening;

Fig. 4 is a side elevation showing a vertical edge of one of the wall panels;

Fig. 5 is a front elevation of one of the panels with portions of the exterior sheathing removed;

Fig. 6 is an end view of one of the panels;

Fig. 7 is a fragmentary section taken on the line 7—7 of Fig. 2 and on a larger scale;

Fig. 8 is an interior elevation of one of the metal fastening devices and adjacent portions of a vertical joint between panels; and

Fig. 9 is a horizontal section taken on the line 9—9 of Fig. 8.

As shown in Figs. 1 and 2, my improved building has a multiplicity of plane, rectangular wall panels 10 joined together at their vertical edges to form an approximately cylindrical enclosure. The lower edges of the several panels rest on a suitable floor 11 provided with joists 12 resting on posts 13 or other suitable foundation members. A sectional roof 14 and a ventilator 15 are also provided but the present invention does not relate to these parts of the building or to the floor construction.

As best shown in Figs. 4 and 5, each of the wall panels 10 is formed from horizontally extending, interior sheathing members 16 and vertically extending, exterior sheathing members 17 secured together in overlapping relation. The several members 16 and 17 are preferably constructed from stock of nominal one inch thick-

ness, with the wood grain extending longitudinally as in ordinary lumber. Tongue and groove connections are preferable between members 17 and the entire surfaces of contact between these outer members and the inner members 16 may be glued to increase the rigidity of the panels, although nailing of the inner and outer members together has been found to be sufficient in most cases.

10 The door panel shown in Fig. 3 is like the others except that it has a suitable rectangular opening 18 formed by cutting away portions of outer sheathing members 19 and inner sheathing members 20. To afford an ample number of continuous reinforcing members crossways of the door, a number of the inner sheathing members 21 are extended entirely across the door opening and panel.

Extending parallel to each of the vertical edges 20 of the several panels 10 is a row of holes 22 for bolts 23. These holes are spaced a substantial distance from the vertical edge surfaces 24 of the panels and these surfaces are formed to lie in vertical planes through the center of the building and to fit together, as best shown in Fig. 9. Each joint between panels has a batten strip 25 covering the end portions of the adjoining members on their inner surfaces from top to bottom and a number of rigid bars 26 extend across each 25 of the strips 25 to coat with the bolts 23 in fastening the panels together. Offset ends 27 of each bar 26 are adapted to be impressed into the inner surfaces of the sheathing members 16 and each bar has a pair of perforations to receive a pair of the bolts 23 which converge inward and have nuts 28 threaded on their inner ends. The holes 22 are preferably arranged to extend substantially perpendicularly to the panels in which they are formed so that when the adjoining panels are erected at an obtuse angle to each other the projecting inner ends of each pair of bolts 23 converge at an acute angle to each other.

45 As shown in Figs. 2 and 7, anchor strips 29 may be fastened in spaced, parallel relation to the outer edges of the floor 11 so that the lower edges of the panels 10 may be placed in abutment with these strips. A door 30 (Fig. 1) of ordinary or suitable construction is provided for the opening 18 of the door panel.

50 Mass production of my improved buildings is facilitated by prefabricating the several wall panels in appropriate sizes so that these plane, rigid units may be stored and shipped compactly and handled and erected easily by two men. It

will be understood that such prefabrication involves the use of jigs and line production methods which insure uniformity in dimensions and accuracy in operations such as the drilling of the holes 22 in the several panels. To erect one of my improved buildings, the foundation and floor may be constructed in the usual manner and then the floor strips 29 may be fastened in place. The batten strips 25 may be fastened to alternate panels as part of the prefabricating operation or they may be attached at any time before the panels are erected.

The panels 10 are erected successively in engagement with the outer surfaces of the several strips 29. As each panel is placed it is connected to another by appropriate manipulation of the bolts 23 and bars 26, the edge surfaces 24 being drawn into abutment with each other by inserting the bolts 23 in the perforations 22, applying the metal bars 26 to the inner ends of the bolts and tightening the nuts 28. As the bolts 23 converge inward, the application of the bars 26 to the inner ends of these bolts may be accomplished with the joint partially open. Subsequently, when each pair of nuts 28 are applied and turned onto the bolts, they not only close the joint forcibly, but also impress the offset ends 27 of the bars 26 into the grain of the inner sheathing members 16 and draw the edges of the adjoining panels firmly against the batten strip 25 to thereby substantially seal the joint and align the adjoining edges of the panels. When all of the wall sections have been erected as described, the roof 14 and ventilator 15 may be constructed or fastened in place.

It will be evident that I provide a number of vertically spaced rows of inner sheathing members extending, end to end, completely around the building and the members in each row are joined together securely, as an endless chain, by the metal bars 26 and bolts 23. These non-expansible confining structures prevent the outward pressure of the grain and other forces from opening the joints or distorting the building. The strength of the encircling structure is substantially increased by my arrangement of the offset ends 27 of the metal bars 26 which are impressed into the members 16 and 21 at points substantially removed from the edges of the panels. By this arrangement a part of the stress which would otherwise be applied to the bolts 23 is distributed directly to the horizontally extending wood members. It will be understood that the vertical load is borne by the outer sheathing members 17 wherein the grain of the wood extends vertically.

Having described my invention, what I claim as new and desire to protect by Letters Patent is:

1. In a wood building of the class described, a plurality of plane wall units disposed at an obtuse angle to each other and each having horizontally extending wood members disposed end to end with such members of the adjoining unit, a batten strip overlapping and aligning the ends of said members and means for fastening the side edges of said units together comprising metal bars extending across said batten strip in contact therewith and in engagement with the members of the respective units and means connecting the ends portions of said bars to said units respectively.

2. In a wood building of the class described, a plurality of plane substantially rectangular wall units disposed at an obtuse angle to each other and each having a complete inner sheathing of horizontally extending wood members, a batten

strip overlapping the inner surfaces of the ends of said members and means for fastening said units together comprising a multiplicity of metal bars extending across said batten strip in contact therewith and severally in engagement with said sheathing members of the respective units and means connecting the end portions of said bars to said units respectively.

3. In a wood building of the class described, a plurality of wall units disposed at an obtuse angle to each other and each having wood members disposed end to end with such members of the adjoining unit, a strip overlapping the inner surfaces of end portions of said members and means for fastening said units together comprising a metal bar extending across said strip in contact therewith, offset end portions on said bar adapted to be impressed into the wood of the adjoining members of the respective units and means connecting said bar to said units respectively and for forcibly impressing the end portions of said bar into said members.

4. In a building of the class described, a plurality of plane substantially rectangular wall units disposed at an obtuse angle to each other and each having horizontally extending inner sheathing members overlapping and secured to vertically extending outer sheathing members and means for joining the side edges of said units together comprising a strip overlapping the several inner sheathing members along the joint, a plurality of metal bars extending across said edges in engagement with said strip and with inner sheathing members of the respective units and means connecting the end portions of said bars to said units respectively.

5. In a wood building of the class described, a plurality of plane substantially rectangular wall units disposed at an obtuse angle to each other and each having horizontally extending inner sheathing members overlapping and secured to vertically extending outer sheathing members, the grain of the several members extending longitudinally thereof and means for joining the side edges of said units together comprising a strip overlapping the several inner sheathing members along the joint, a plurality of metal bars extending across said edges in engagement with said strip and with inner sheathing members of the respective units and bolts connecting the end portions of said bars to said units respectively, said bolts converging obliquely inward and having nuts threaded on their inner ends whereby the edges of the units may be forcibly drawn together and sealed against said strip.

6. A grain bin comprising, a multiplicity of plane, substantially rectangular panels severally disposed in vertical planes and at obtuse angles to each other, each of said panels comprising substantially horizontally extending inner sheathing members secured to outer sheathing members and means for joining the vertical edges of said panels together comprising, metal bars extending horizontally in engagement with the inner surfaces of the adjoining panels, each of said bars having offset portions adapted to be impressed into the inner sheathing members of adjoining panels at points spaced from the edges of the panels and means extending through perforations in the bars for connecting each bar to the adjoining panels.

7. A grain bin comprising, a multiplicity of plane, substantially rectangular panels severally disposed in vertical planes and at obtuse angles to each other to form the walls of the bin, each

of said panels comprising substantially horizontally extending inner sheathing members secured to outer sheathing members and means for joining the vertical edges of said panels together comprising, a strip extending along each joint in engagement with the ends of the adjoining inner sheathing members, metal bars extending across said strips in contact therewith and in engagement with the inner surfaces of the adjoining panels and means extending through perforations in the panels and bars for connecting each bar to the adjoining panels, a series of said bars being disposed in a horizontal row around the bin to form with the inner sheathing members a continuous, peripheral, reinforcing structure.

8. In a sectional building, plane wall units disposed at an obtuse angle to each other and each having wooden tension members disposed with the grain of the wood in end to end relation to that of similar members of the adjoining

5 unit, metal bars extending across the joint between units in engagement with the tension members of the respective units and within the obtuse angle between them, offset end portions formed on said bars to be impressed into the cross grain of said members at points spaced from the ends thereof and means for fastening said bars to the tension members and for forcibly impressing said offset portions into flat 10 surfaces of said members to form interlocking indentations therein when the joint is closed.

9. The structure defined in claim 8 in which said fastening means comprise bolts engaging the bars and tension members, extending through perforations spaced from the joint between units and converging obliquely inward within the angle formed by the said tension members and nuts threaded on said bolts whereby the units may be drawn forcibly together at 15 the joint by turning the nuts on the bolts.
